US00D358211S

United States Patent [19]

Cohen

[11] Patent Number: Des. 358,211

[45] Date of Patent: ** May 9, 1995

[54] **UNITARY TIBIAL COMPONENT FOR PROSTHETIC KNEE IMPLANT**

[75] Inventor: **Robert C. Cohen**, Rockaway Township, Morris County, N.J.

[73] Assignee: **Osteonics Corp.**, Allendale, N.J.

[**] Term: **14 Years**

[21] Appl. No.: **844,823**

[22] Filed: **Feb. 28, 1992**

[52] U.S. Cl. **D24/155**

[58] Field of Search **D24/155; 623/18, 20, 623/21**

[57] **CLAIM**

The ornamental design for a unitary tibial component for prosthetic knee implant, as shown and described.

DESCRIPTION

FIG. 1 is a top perspective view of a unitary tibial component for prosthetic knee implant embodying my new design;

FIG. 2 is a top plan view thereof;

FIG. 3 is a front elevational view thereof;

FIG. 4 is a rear elevational view thereof;

FIG. 5 is a side elevational view of one side thereof, the other side being a mirror image thereof; and,

FIG. 6 is a bottom plan view thereof.

FIG. 1

FIG. 2

FIG. 3

FIG. 4

FIG. 5

FIG. 6
